U.S. Appl. No. 29/398,483, filed Aug. 1, 2011, entitled Soft Chest Protector.

* cited by examiner

Primary Examiner — Susan Bennett Hattan*Assistant Examiner* — Barbara B Lohr(74) *Attorney, Agent, or Firm* — Faegre Baker Daniels LLP(57) **CLAIM**

The ornamental design for a soft chest protector, as shown and described.

DESCRIPTION

FIG. 1 is a perspective view of a first embodiment of a soft chest protector.

FIG. 2 is a front view of a first embodiment of a soft chest protector.

FIG. 3 is a back view of a first embodiment of a soft chest protector.

FIG. 4 is a first side view of a first embodiment of a soft chest protector, the second opposing side being a mirror image thereof; and,

FIG. 5 is a top view of a first embodiment of a soft chest protector.

The broken lines in the Figures do not form a part of the claimed design.
